UNITED STATES PATENT OFFICE.

FRANK A. FOUTS, OF WASHINGTON, DISTRICT OF COLUMBIA.

SPINNING-TOP.

SPECIFICATION forming part of Letters Patent No. 267,867, dated November 21, 1882.
Application filed October 20, 1882. (No model.)

To all whom it may concern:

Be it known that I, FRANK A. FOUTS, a citizen of the United States, residing at Washington, in the District of Columbia, have invented certain new and useful Improvements in Children's Spinning-Tops, of which the following is a specification, reference being had therein to the accompanying drawings.

My invention relates to children's spinning-tops.

It consists in providing the shank end or peg end of a cone-shaped spinning-top with a hole, staple, or catch adapted to secure an end of the cord; also, in providing said top with a top and bottom spindle and a cage or other receptacle adapted to receive and inclose the top, said cage being provided with means for securing the spindles, but which permit the top and spindles to revolve freely therein.

The object of my invention is to effect the return of a top to the hand of the operator after the cord has been wound on the body of the top, the lower end of the cord secured in the hole, staple, or catch in the peg end of the top, and the loose end of the cord secured between the fingers by the button—that is to say, a top which may be thrown outward on the cord and returned on said cord to the hand of the operator by a single throw, all of which will more fully appear by reference to the accompanying drawings, in which—

Figure 1 represents a side elevation of a top provided with a hole through the shank part of its peg, the end of the spinning-cord being secured therein. Fig. 2 is also a side elevation of a top with a hole in the shank of its peg. A fragment of the lower end of the cord is secured in said hole by means of a knot on the extreme end of said cord. Fig. 3 is a side view of a top provided with a staple on its small end, in which the lower end of the cord is secured, the other portions of the cord being wound upon the body of the top from the small end upward, the loose end of the cord being provided with a ball or button, by means of which said end is secured between the fingers when the top is thrown. Fig. 4 is a side view of a top provided on its small end above the peg with a spring-strap. The upper end of the strap is screwed or fixed to the body of the top, while the lower end thereof is above and rests against the side of the peg. The center of the strap is bent outward. The strap

is adapted to receive and secure the lower end of the cord by spinning out the loose end of said strap and sliding the cord thereunder. Fig. 5 is a front view of the top, showing a face view of the spring-strap with a fragment of the cord secured therein, also a perspective of the strap detached. Fig. 6 represents a top having a hole in its peg end, also a cord provided on one end with a hook and on the other end with a recessed sliding button, the hook being adapted to engage the hole in the top. When it is desired to spin the top in the ordinary old-fashioned manner the button may be slid to the hook end of the cord and the hook secreted in the recess of the button, thus presenting an ordinary cord—i. e., a cord provided on one end with a knot and on the other with a button. Fig. 7 is a side view of a top provided with a cylindrical shank above a peg and shoulder, the intersection of the small end of the top and cylindrical shank forming a circumferential groove, the small end of the top being of less diameter than the shank. Said shank is provided with a hole and also with a spring-strap similar to the strap shown in Figs. 4 and 5. The cord may be engaged in either the hole or strap and the return feature effected. Fig. 8 is a front elevation of a top inclosed within a wire frame or cage. The upper and the lower ends of the top are each provided with a spindle that fits into bow-straps secured to the inner side of the frame, and the top is adapted to revolve freely in its bearings. A pear-shaped opening is made in the face of the frame, whereby the cord may be wound upon the body of the top without being brought in frictional contact with the sides of said opening. The strap on the upper side of the frame is given a downward bow-shape. The frame at that end presents a circular opening save where it is spanned by the strap. Within said opening and above the strap, and secured to the spindle, is a crank which is adapted to wind the cord on the body of the top. The cord is secured to the top through the hole in the small end, the cord in this view being wound upon the body of the top. Fig. 9 represents a hand holding the top. The lower end of the cord is secured in the hole in the small end, and the other portions thereof are wound upon the body of the top, the loose end being secured between the fingers by the button. When the parts are thus united and the

top forcibly thrown from the hand it will pass to the end of the cord and return to the hand of the operator by a single throw, (not permitting the top to strike the floor.) The cord 5 unwinds from the top on its outward passage and rewinds thereon in returning. When the top reaches the end of the cord it is of course spinning rapidly, which causes it to spin first with its head downward, and then instantly 10 rise gyroscopically, whereby the cord is given a winding start on the lower end of the top, and the top forced by its rapid revolutions to ascend the cord and wind the same on its body in the ascent, whereby the operator is enabled 15 to catch it like a return-ball. Fig. 10 represents the top half-way out on the cord on its outward passage. The continuation in dotted lines shows the top at the end of the cord. The top is presumed to be revolving rapidly, 20 whereby it engages and ascends the cord, as shown in Fig. 11; and Fig. 12 represents a boy operating the top, showing the proper relative positions of his body, hand, and arm.

Similar letters refer to similar parts throughout the several views.

25 The letter A represents the body of the top, and B the hole through the small end thereof.

B' is a staple secured in the circumferential groove C of the top, or at a point near the 30 small end of said top.

B² is a spring-strap fixed to the lower or small end of said top. It is adapted to engage the knotted end of the cord when placed thereunder. The cord may be easily secured there- 35 by or released therefrom.

D represents the peg of the top.

E is the cord, having knotted ends, and provided with a recessed sliding button, F, Fig. 6.

E' is a hook on cord E. When the hook is 40 not used a recessed button is not required; an ordinary button will suffice. A cord provided with a hook and sliding recessed button are no part of the invention presented herewith, inasmuch as they are made the subject of 45 claims in an application filed by me in the United States Patent Office on September 16, 1882.

G represents a cylindrical shank, provided on its lower end with a shoulder, G', and on 50 its side with a spinning-strap, B², (similar to the strap shown in Figs. 4 and 5;) and B is a hole through said shank.

H, Fig. 8, represents a wire cage or frame provided with a pear-shaped opening, H'.

I is a bow-strap, having a central small opening adapted to receive and secure the spindle I' on the small end of the top.

I² is a shoulder between the strap I and hole B. Said shoulder forms the abutment 60 for the lower wrap of cord and prevents said cord from engaging and winding on the spindle I'.

J is a bow-strap in the upper side of the cage, and J' is a spindle on the upper part of 65 the top, which passes through a small opening in the bow J, and by means of which the upper part of the top is secured in the frame.

J² is a crank fixed to the spindle J' above the strap J. By means of the crank the cord may be wound upon the body of the top in 70 the cage. An opening is made in the upper part of the top, which is spanned by the strap J, said strap being secured to the sides thereof. The crank is held below the periphery of the spherical cage, thereby protecting 75 said crank. The object of the top and cage is to effect their return to the hand when thrown downward on the cord (not permitting the cage to strike the floor) by first securing the lower end of the cord in hole B and winding 80 the cord on the cone from the small end upward, then securing the cord between the fingers by the button and throwing the cage downward, which action causes the device to pass to the end of the cord and return to the 85 hand of the operator by a single throw. The cord unwinds from the body on the downward passage and rewinds thereon in ascending. The cage is made of light material, whereby the rapid revolutions of the top therein and 90 on the cord may carry it upward to the hand when forcibly thrown outward.

On September 16, 1882, I filed an application for patent in the United States Patent Office, which consists in providing the small end of a 95 cone-shaped spinning-top with a circumferential groove and a circumferential flange; also, in a spinning-cord provided on one end with a hook and on the other end with a recessed button adapted to slide on the cord. The top, 100 cord, and attachments therein set forth and claimed co-operate to effect the return of the top to the hand of the operator when the hook on the cord is secured in the circumferential groove of the top, the cord wound upon the 105 body of said top, the loose end of the cord secured between the fingers by the button, and the top thrown outward on the cord. The effect of the top and means specified in said application is similar to the effect of the top, cord, 110 and connecting means herein shown and claimed—that is to say, the return of the top to the hand when thrown is similar in both cases. In said former application the top and cord therein shown are connected by means in 11 which the top may freely revolve when said top is thrown outward on the cord, as specified, the return of the top on the cord being effected by the frictional contact between the cord and the circumferential grooves on the top. In the device herein specified and claimed the return 115 feature is effected by providing the top with means adapted to engage and secure an end of the cord thereto, the connecting means firmly securing the top by its small end, whereby 12 every revolution of the top must either wind or unwind the cord from its body. Therefore by throwing the top in the manner set forth it is forced to pass to the end of the cord, its revolu- 125 ble velocity increasing until it reaches the end of said cord, when the cord quickly re-engages with the body of the top and it ascends to the hand of the operator, the top passing out on one side of the cord and returning on the other

side thereof. The rapid revolutions of the top when it is at the end of the cord cause it to throw its head upward gyroscopically, in which position it re-engages the cord and ascends to the hand.

With this application and of even date here-with is filed a third application specifying and claiming certain improvements on my application of September 16, 1882.

Having thus described my invention, what I claim as new, and desire to secure by Letters Patent, is—

1. A spinning-top having a body adapted to receive a cord by which it is spun, said top being provided on its small end with a hole or equivalent means for securing the cord and preventing the swivel thereof, whereby the cord may be wound upon the body of the top and the top thrown and returned to the hand of the operator by a single throw, the cord being first wound and then rewound on the body of the top, the loose end of the cord remaining in the hand during the operation, substantially as described, and for the purposes set forth.

2. A spinning-top having a body adapted to receive a cord by which it is spun, and a cord to spin the same, said top being provided on its small end with a hole or equivalent means for securing the cord and preventing the swivel thereof, whereby the cord may be wound upon the body of the top and the top thrown outward and returned to the hand of the operator by a single throw, the cord being first unwound and then rewound on the body of the top, the loose end of the cord remaining in the hand during the operation, substantially as described, and for the purposes set forth.

3. A cone-shaped spinning top provided with means on its small end adapted to secure an end of the spinning-cord and prevent the swivel thereof, in combination with a spinning-cord, whereby the cord may be wound upon the body of the top, the top thrown outward and returned to the hand of the operator by a single throw, the cord being first unwound and then rewound on the body, the loose end of the cord remaining in the hand during the operation, substantially as described, and for the purposes set forth.

4. A cone-shaped spinning-top provided with a hole or equivalent means on its small end for securing an end of the spinning-cord and preventing the swivel thereof, in combination with a spinning-cord, whereby the cord may be wound upon the body of the top, the top thrown outward and returned to the hand of the operator by a single throw, the cord being unwound in the outward passage of the top and rewound thereon in the ascent, the loose end of the cord remaining in the hand during the operation, substantially as and for the purposes set forth.

5. A spinning-top provided on its small end with a cylindrical shank having cord-secur-ing means thereon, in combination with a spinning-cord, substantially as described, and for the purposes set forth.

6. A cone-shaped spinning-top having a body adapted to receive a cord by which it is spun, and a cord to spin the same, said top being provided on its small end with means for securing an end of the cord to said small end, in combination with a case or cage provided with means adapted to receive the top and rev-olubly secure the same therein, whereby the cord may be wound upon the top and the top and case thrown outward and returned to the hand of the operator by a single throw, the cord being first unwound and then rewound on the top, the loose end of the cord remain-ing in the hand during the operation.

7. A cone-shaped spinning-top having a body adapted to receive a cord by which it is spun, and a cord to spin the same, said top being provided on its small end with means for securing an end of the cord to said small end of the top, in combination with a cage or case provided with means adapted to receive the top, the top being provided with top and bottom spindles, by means of which it is revolu-bly secured in the case or cage, substantially as described, and for the purposes set forth.

8. A cone-shaped spinning-top having a body adapted to receive a cord by which it is spun, and a cord to spin the same, said top being provided with top and bottom spindles and means on its small end for connecting the cord thereto, in combination with a case or cage adapted to receive the spindles, one of said spindles being provided with a crank, by means of which the top is turned and the cord wound on the body thereof, whereby the cord may be wound on the top and the top and cage thrown and returned to the hand of the operator by a single throw, the loose end of the cord remaining in the hand during the operation, substantially as set forth.

9. A cone-shaped top having a body adapted to receive a cord by which it is spun, and a cord to spin the same, said top being provided with top and bottom spindles and means on its small end for connecting the cord thereto, in combination with a cage or case provided with bearings adapted to receive the spindles, one of the said spindles being provided with a crank, said case having a side opening adapted to receive the cord, whereby the cord may be wound upon the body of the top and the top and case thrown outward and returned to the hand of the operator by a single throw, the loose end of the cord remaining in the hand during the operation.

10. The combination of a cone-shaped spin-ning-top, of a case adapted to receive the same, of a spinning-cord, and of means for rev-olubly securing the top in the case.

In testimony whereof I affix my signature in presence of two witnesses.

FRANK A. FOUTS.
